UNITED STATES PATENT OFFICE.

PETER RENNER, OF CINCINNATI, OHIO.

CIGAR-CASE.

No. 848,854.

Specification of Letters Patent.

Patented April 2, 1907.

Application filed April 20, 1906. Serial No. 312,854.

To all whom it may concern:

Be it known that I, PETER RENNER, a citizen of the United States, residing at Cincinnati, in the county of Hamilton and State of Ohio, have invented certain new and useful Improvements in Cigar-Cases; and I do hereby declare the following to be a full, clear, and exact description of the invention, such as will enable others skilled in the art to which it appertains to make and use the same.

This invention relates to improvements in cigar-cases, and more particularly relates to cases for receiving lighted cigars.

15 It frequently occurs that a smoker is compelled while carrying a lighted cigar to enter buildings, cars, and other places where smoking is prohibited, and in many instances this arises shortly after a cigar has been lighted.

20 Obviously the smoker does not care to discard the cigar under these conditions, and it is therefore desirable that some provision be made whereby the cigar may be retained by the smoker.

25 The present invention aims to provide a case that may be used under these circumstances, enabling the smoker to place the cigar therein while lighted and to conveniently carry the same within a pocket without

30 injury to the garments or to the person injury to the cigar, or offense to persons in whose favor the prohibitions against smoking are enforced.

It is also a further object of the present invention to provide a case of the character 35 mentioned the construction of which is simple and inexpensive, one which will effectually protect the cigar and prevent the ashes from the lighted end contacting with the 40 butt of the cigar, and also whereby the cigar upon opening the case will be conveniently positioned for its ready removal from the case.

With these general objects in view and others, which will appear as the nature of the 45 improvements is better understood, the invention consists, substantially, in the novel construction, combination, and arrangement of parts hereinafter fully described, illustrated in the accompanying drawings, and 50 pointed out in the appended claims.

In the drawings, Figure 1 is a perspective view of a cigar-case embodying the herein-described invention. Fig. 2 is a side elevation thereof, the case being open. Fig. 3 is a 55 plan view, the case being in the position illus-

trated in Fig. 2. Fig. 4 is a longitudinal sectional view of the case when closed. Fig. 5 is a transverse sectional view, the case being closed, as in Fig. 4. Fig. 6 is a detail perspective view of the resilient support.

Referring in detail to the drawings, the numeral 1 designates the body of the herein-described case, which body is formed of a plurality of members 2, the contiguous edges of 60 which are connected together by a hinge 3, whereby said members may have relative movement. The members 2 may be formed of any material—such as metal, papier-mâché, hard rubber, or wood fiber—but 65 they are preferably formed of aluminium, because of its lightness and wearing qualities.

Each of the members 2 is provided with a lining 4, of refractory material, such as asbestos, the purpose of this lining being to 70 provide a contact-surface for the lighted end of the cigar placed in the case and which will act as an insulation, as well as not be consumed, and by reason of this lining for each of the members it is apparent that when the 75 case is closed the lighted end of the cigar will be entirely enveloped by the refractory material, thereby preventing ignition of the clothing or bodily harm resulting from the lighted cigar.

85 Arranged at the interior of one of the members is a longitudinally-extending resilient strip 5, one end of which is provided with engaging prongs 6, designed to pass through said member and be riveted thereto, thus 90 fixedly connecting the strip 5 with said member. The other end of said member is free, being provided with a transversely-extending integral curved support 7, designed to receive the butt of the cigar, and when the case 95 is closed the pressure of the other member upon the cigar will force the support 7 and the strip 5 against the inner face of the member carrying said strip, thus enabling the cigar to lie closely within the case and remain 100 therein. The strip 5 is slightly bent, so that when the free end thereof is not impeded in its action the same will move away from the inner side of the member to which the strip is attached for a purpose to be presently stated.

105 The pressure of the strip 5 and the support 7, moreover, will hold the butt of the cigar in proper place, and consequently as the cigar is held in substantially a fixed position the ashes from the lighted end thereof will be 110 prevented gathering around the butt. The support 7 also adjusts itself to the shape of

the cigar irrespective of its shape and effectually holds the same in position.

To hold the case in closed position one of the members 2 is provided with a suitable catch 8, designed to engage the other member and through the medium of which both of the members will be held in closed relation.

In the use of the herein-described case the 10 lighted cigar is placed upon the member carrying the strip 5 and the support 7, the butt of the cigar resting upon said support and the lighted end resting upon the refractory lining 4. The case is now closed, in which action 15 the cigar is forced into contact with the inner faces of the two members 2 and the fastener 8 secured to hold the members 2 closed. The case may now be placed within the 20 pocket of the user without liability of igniting the clothing or otherwise doing bodily harm, and the cigar may be retained in the case as long as desired. When it is desired 25 to remove the cigar, the fastener 8 is operated to release the members 2, whereupon the resiliency of the strip 5 asserts itself, raising the support 7, as well as the opposing member 2, and thereby elevating the butt-end of the cigar to a position to be conveniently 30 grasped by the smoker, and in this position the cigar may be readily removed.

While the case is illustrated and described as being but a single unit or adapted to receive but a single cigar, it is obvious that the same may be made in a plurality of units or 35 designed to receive a plurality of cigars.

Having thus described the invention, what is claimed as new, and desired to be secured by Letters Patent, is—

1. A case of the character described, comprising a plurality of members hingedly con-

nected, a refractory lining at the interior of each of said members with which the lighted portion of the cigar is adapted to contact, a resilient strip having one of its ends connected to the inner side of one of said members 45 and its other end free, a support carried by the free end of said strip and arranged transversely thereof, said support receiving the cigar and serving to elevate the same under the movement of said strip to position the 50 cigar for ready removal when the case is opened, and also coacting with the opposite member to hold the cigar in position in the case when the latter is closed, and a fastener for retaining the members in closed relation. 55

2. A case of the character described, comprising a plurality of members hingedly connected, a refractory lining at the interior of each of said members with which the lighted portion of the cigar is adapted to contact, a resilient strip arranged at the inner side of one of said members and provided at one of its ends with engaging prongs for fastening said strip to said member, the other end of said strip being free, a support carried by the 60 free end of said strip and arranged transversely thereof, said support receiving the cigar and serving to elevate the same under the movement of said strip to position the cigar for ready removal when the case is 65 opened, and also coacting with the opposite member to hold the cigar in position in the case when the latter is closed, and a fastener for retaining the members in closed relation. 70

In testimony whereof I affix my signature 75 in the presence of two witnesses.

PETER RENNER.
